AUTOMATIC PAPER FEED CUTOFF

Filed May 13, 1947

INVENTOR
ALFONSO MARTELL

BY *W.M. Keister*

ATTORNEY

1. A printing press having printing cylinders and means for conveying sheets to and from the cylinders, including a rock shaft and a feeding mechanism for feeding sheets to the cylinders, and means for stopping the feeding mechanism when the rock shaft is stopped, said means for stopping the feeding mechanism including a magnet having a plunger bolt slidably guided in said magnet, a plunger rod reciprocatably guided transverse to the end of said bolt when retracted, a set screw connecting the plunger rod to the rock shaft, and a switch box mounted under the path of the feeding mechanism, said switch box containing a normally closed switch comprising a contact and a leaf spring biased from the contact, and a feeler connected to the leaf spring and adapted to be pressed beyond the plane of the printed sheets when no sheet is present, thereby to open the switch.

UNITED STATES PATENT OFFICE

AUTOMATIC PAPER FEED CUTOFF

Alfonso Martell, Bloomfield, N. J.

Application May 13, 1947, Serial No. 747,682

8 Claims. (Cl. 271—57)

1. This invention relates to printing presses and

more particularly to attachments for printing presses having one or more printing cylinders and means for conveying sheets to and from the cylinders, though it is noted that in some of the claims the invention is not limited to printing presses.

One object of the invention is to provide an improved attachment of this kind which automatically stops the feeding means when the sheets are not properly delivered from the printing cylinders, thereby to prevent injury to the press or form and waste of paper.

Other objects of the invention are to provide an improved attachment of this kind which is adaptable for different types of presses, or feeding means and which may be attached to presses at different locations which will not interfere with the proper operation of the press.

Additional objects of the invention are to effect simplicity and efficiency in such attachments and to provide an extremely simple attachment of this kind which is reliable in operation, easy to operate and economical to manufacture and install.

Still other objects of the invention will appear as the description proceeds; and while herein details of the invention are described in the specification and some of the claims, the invention as described in the broader claims is not limited to these, and many and various changes may be made without departing from the scope of the invention as claimed in the broader claims.

The inventive features for the accomplishment of these and other objects are shown herein in connection with an automatic paper feed cut-off attachment herein shown in combination with a printing press having printing cylinders and conveyor means receiving and conveying printed sheets from the cylinders. The press is shown as provided with previously known mechanism for feeding sheets to the cylinders including a rock shaft and means for stopping the mechanism when the rock shaft is stopped.

My improved attachment comprises a magnet support adapted to be mounted on the press frame and supporting an electromagnet having a plunger bolt slidably guided in said magnet and adapted when the magnet is energized to be withdrawn toward the magnet. A plunger rod reciprocatably guided transverse to the end of said bolt when retracted is connected to the rock shaft and adapted to be stopped by the bolt when not retracted thereby to stop the rock shaft. A switch box mounted under the path of the

printed sheets contains a normally closed switch comprising a contact and a leaf spring biased from the contact, and a feeler connected to the leaf spring and adapted to be pressed beyond the plane of the printed sheets when no sheet is present, thereby to open the switch.

Conductors connect the switch and the coil of the magnet in series circuit, whereby when no sheet is present, the switch is opened, the magnet deenergized, and the bolt, rock shaft and feeding mechanism stopped.

In the accompanying drawing showing, by way of example, one of many possible embodiments of the invention,

15 Fig. 1 is a fragmental somewhat diagrammatic side elevation of the printing press showing the switch box and magnet support mounted on the frame of the press; and

20 Fig. 2 is a fragmental side elevation showing the switch, magnet, plunger and the mounting means therefor.

My improved automatic paper feed cut-off is shown by way of example, in combination with a printing press 10 having impression cylinders 11, 12 and a reversing cylinder 13 therebetween; though it is noted that the invention is suitable for single cylinder and other types of presses or machines. Endless tapes 14 mounted on rollers 15, 16 mounted on shafts 17, 18 have approximately horizontal upper courses receiving sheets of paper 20, one at a time, from the second cylinder 12. A sheet feeding mechanism 21 of the general character of that shown in United States Patent No. 1,620,800 of C. E. Christopher, issued March 15, 1927 feeds the sheets to the first cylinder 11. Said feeding mechanism has an automatic cut-off device including a normally oscillatory rock shaft 46, control means for stopping the rock shaft and means for stopping the feeding mechanism whenever said rock shaft 46 is stopped. Only such part of said mechanism is shown as is necessary to show said rock shaft 46, which is herein designated by reference numeral 46.

With the press herein shown I provide a pair of brackets 23 secured on the printing press members 24 at opposite sides of the press. A rod 25 mounted in said brackets 23 transversely of the press, approximately over the discharge part of the second printing roller 12 carries a bracket 26 having a vertical bore 27 receiving a vertical rod 28 secured adjustably fast in said vertical bore 27 by means of a set screw 29. A magnet support 30 comprising a rear wall 31, a floor 32 joining said wall and having a rectangular opening

33 near its mid-part, and a downturned flange 34 on the front edge of the floor provided with a round opening 35 near its mid-part, is provided on the rear face of the rear wall 31 with a lug 36 having a vertical bore 37 adjustably receiving said vertical rod 28 held fast therein by a set-screw 39.

A rectangular magnet frame 40 secured on said rear wall has fixed tubular central vertical core 41 of magnetic material on which is received a solenoid 42. A plunger core 43 slidably in said tubular core has a lower extension bolt 45 in said rectangular opening 33 and is adapted when the magnet is deenergized to extend below the level of the round opening 35 and when the magnet is energized to be withdrawn above said level as shown at the dotted lines 45a.

A cover 47 for the magnet comprising integral side, top and front walls 49, 50, 51, the lower edge of the front wall 51 having small end notches 52, and therebetween a large middle notch 53 registering with said round opening 35. Clamping screws 54 in the downturned flanges are received in said small notches 52 and serve for clamping the cover 47 in place.

An oscillatory shaft 56 mounted across the press over the second cylinder carries a pair of upwardly pointing long and short lever arms 57, 58. A rocker arm 59 fast on said rock shaft 46 of the feeder cut-off mechanism is connected by a link 60 to lever arm 57. A horizontal plunger rod 61 is pivoted to the other arm and is reciprocatingly in said round opening 35 and middle notch 53, at all times out of contact with said extension bolt 45 when the bolt is retracted.

Said bolt when the magnet is deenergized is adapted to drop to the position shown and to stop said plunger rod, said rock shaft and said feeding mechanism.

A bar 64 mounted between bearings of said roller shafts 17, 18 between the planes of the upper and lower courses of the tapes 14 and between and remote from the right and left marginal tapes supports a switch box 65 mounted fast on said bar between said courses, the upper part of the box being just under the plane of the upper course of tapes 14 and the sheet 20 of paper carried thereon. A switch 66 in said box may be of any suitable type, for instance, the switch shown in United States Patent No. 1,960,020 issued May 22, 1934, to P. K. McGall, and comprises upper and lower fixed contacts 67, 68 and a leaf spring 69 biased from and movable to the lower contact 68. Conductors 70, 71, 72 connect said solenoid 42 and switch 66 in series between the terminal of a suitable current source 73. An upright rod 74 resting on said leaf spring 69 engages under a feeler finger 75 pivoted at 76 in the upper part of the switch box at the end nearest the printing cylinders and is adapted to be pressed upwardly by said rod and leaf spring beyond the plane of the sheet of paper 20 when no sheet is present, thereby to open the switch and deenergize the magnet, the finger being adapted to be pressed down by a sheet 20 when present on the tapes over the switch, thereby to close the switch and energize the magnet. Said switch 66 is in such a position under the sheets that in normal operation a sheet is over the switch to depress the finger 75 and close the switch and energize the magnet and retract the extension bolt 45 at the time that the plunger rod 61 is normally projected across the path of the bolt; whereby if a sheet 20 should fail to be fed or should get wrapped around a cylinder or

should for that or any other reason fail to be on the tapes 14 over the switch 66 when the plunger rod 61 is about to be projected across the path of the bolt, the finger 75 will be raised, the switch opened, the magnet deenergized, the bolt 45 dropped and the plunger 61, the rock shaft 46 and the feeding mechanism stopped, thus to prevent waste of paper or injury to the press.

The operation will be easily understood from the foregoing. The press is operated in the ordinary way, the bolt 45 being held retracted by closing a starting switch 76 until a sheet is over the switch 66, closing the switch 66 and holding the bolt 45 retracted. Then the switch 76 is opened and the machine is continued in operation in the ordinary way; but if for many reason a sheet 20 should not appear over the switch, the switch will open and the feeding mechanism stop, until the operation is corrected.

I claim as my invention:

1. An attachment for use on a printing press having a printing cylinder, conveyor means having courses receiving printed sheets from the press; a mechanism for feeding sheets to the press, including an oscillatory part and means for stopping the mechanism when said part is stopped; said attachment comprising in combination a magnet; a guided plunger bolt adapted when the magnet is energized to be withdrawn toward the magnet; a plunger rod slidably reciprocatorily guided transverse to said bolt at the end of the bolt when the bolt is retracted, and connected to said part and adapted to be stopped by the bolt when not retracted thereby to stop said part; a switch mounted under the path of the printed sheets and connected in series circuit with the magnet; a feeler connected to the switch and adapted to be pressed beyond the plane of the printed sheets when no sheet is present, thereby to open the switch.

2. An attachment for use on a printing press having a printing cylinder; conveyor means having courses receiving printed sheets from the cylinder; a mechanism for feeding sheets to the cylinder, including a rock shaft, and means for stopping the mechanism when the rock shaft is stopped; said attachment comprising in combination a magnet support; an electromagnet on said support; a plunger bolt slidably guided in said magnet and adapted when the magnet is energized to be withdrawn toward the magnet; a plunger rod slidably reciprocatorily guided transverse to said bolt when retracted and connected to the rock shaft and adapted to be stopped by the bolt when not retracted; a switch mounted under the path of the printed sheets and comprising a contact and a leaf spring biased from the contact; a source of current; conductors connecting the switch and magnet in series between the terminals of the source; a feeler connected to the leaf spring and adapted to be pressed by the spring beyond the plane of the printed sheets when no sheet is present, thereby to open the switch, deenergize the magnet and stop the rock shaft.

3. An attachment for use on a printing press having printing cylinders; tapes having horizontal courses receiving sheets from the cylinders; a feeding mechanism for feeding sheets to the cylinders, including a rock shaft, and means for stopping the mechanism whenever said rock shaft is stopped; said attachment comprising in combination a magnet support comprising a floor having a rectangular opening and a downward flange provided with a round opening; a magnet frame

secured on said support having a tubular vertical core; a solenoid on said core; a plunger slidably in said core and having an extension bolt in said rectangular opening and adapted when the magnet is energized to be withdrawn above said level; a horizontal plunger rod slidably reciprocatory in said round opening out of contact with said bolt when retracted; a switch box mounted between said courses of tapes, the upper part of the box being just under the plane of the upper course; a switch in said box comprising a lower contact and a leaf spring biased from the lower contact; a source of current; conductors connecting said solenoid and switch in series between the terminals of said source; an upright rod resting on said leaf spring; and a feeler finger pivoted in the upper part of the switch box at the end nearest the cylinders and adapted to be pressed upwardly by said rod and leaf spring beyond the plane of the sheets when no sheet is present, thereby to open the switch and deenergize the magnet, whereby if a sheet should fail to be present over the switch when the plunger rod is about to be projected, the finger will be raised, the switch opened, and the rock shaft stopped.

4. An attachment for use on a printing press having printing cylinders; a reversing roll therebetween; endless tapes having horizontal courses receiving sheets of paper from the second cylinder, and a feeding mechanism having an automatic cut-off device including a normally oscillatory rock shaft, control means for stopping the rock shaft, and means for stopping the mechanism whenever said rock shaft is stopped; said attachment comprising in combination a pair of brackets secured on the printing press frame at opposite sides of the frame; a rod mounted in said brackets transversely of the press over the second printing roller; a bracket mounted on said rod and having a vertical bore; a vertical rod secured adjustably fast in the vertical bore; a magnet support comprising a rear wall, a floor joining said wall and having a rectangular opening near its mid-part, and a downturned flange on the front edge of the floor provided with a round opening near its mid-part; the rear face of the rear wall having a lug having a vertical bore adjustably receiving said vertical rod fast therein; an electromagnet on said support; a plunger bolt slidably guided in said magnet and rectangular opening and adapted when the magnet is energized to be withdrawn toward the magnet; a plunger rod slidably reciprocatorily guided in said round opening transverse to said bolt when retracted and connected to the rock shaft and adapted to be stopped by the bolt when not retracted; a switch mounted under the path of the printed sheets and comprising a contact and a leaf spring biased from the contact; means connecting the switch and magnet coil in series circuit; a feeler connected to the leaf spring and adapted to be pressed beyond the plane of the printed sheets when no sheet is present, thereby to open the switch.

5. An attachment for use on a printing press having a printing cylinder; conveyor means having courses receiving printed sheets from the cylinder; a mechanism for feeding sheets to the cylinder, including a rock shaft, and means for stopping the mechanism when the rock shaft is stopped; said attachment comprising in combination a magnet support having a rear wall, and a floor having a rectangular opening therein and a downturned flange having a round opening therein; a rectangular magnet frame secured on

said rear wall and having a fixed tubular central vertical core; a solenoid on said core; a plunger core slidable in said tubular core and having a lower extension bolt in said rectangular opening and adapted when the magnet is deenergized to extend below the level of the round opening and when the magnet is energized to be withdrawn above said level; an oscillatory shaft mounted across the press and carrying a pair of upwardly pointing lever arms; a rocker arm fast on said rock shaft of the feeder cut-off mechanism linked to one of said lever arms; a horizontal plunger rod pivoted to the other arm and slidably reciprocatory in said round opening at all times out of contact with said bolt when the core is retracted; a cover for the magnet comprising integral side top and front walls, the lower edge of the front wall having small end notches and therebetween a large central notch receiving the plunger rod; clamping screws in the downturned flanges received in said small notches for clamping the cover in place; a feeler for feeling the sheets in the conveyor means; and means operated by the feeler when a sheet is present in the conveyor means to energize said magnet.

6. An attachment for use on a printing press having a printing cylinder; conveyor means having courses receiving printed sheets from the cylinder; a mechanism for feeding sheets to the cylinder, including a rock shaft, and means for stopping the mechanism when the rock shaft is stopped; said attachment comprising in combination a magnet support; an electro-magnet on said support; a bolt slidably guided in said magnet and adapted when the magnet is energized to be withdrawn toward the magnet; a plunger rod slidably reciprocatorily guided transverse to said bolt when retracted and connected to the rock shaft and adapted to be stopped by the bolt when not retracted; a switch mounted under the path of the printed sheets and comprising a contact and a leaf spring biased from the contact; a source of current; and a feeler connected to the leaf spring and adapted to be pressed beyond the plane of the printed sheets when no sheet is present, thereby to open the switch; said switch being in such a position under the sheets that in normal operation a sheet is over the switch to close the switch and energize the magnet and retract the bolt at the time that the plunger rod is normally projected across the path of the bolt; whereby if a sheet should fail to be fed or get wrapped around a cylinder and should for that or any other reason fail to be on the tapes over the switch when the plunger rod is about to be projected across the path of the bolt, the finger will be raised, the switch opened, the magnet deenergized, the bolt dropped and the rock shaft stopped; thus to prevent waste of paper and injury to the press.

7. An attachment for use on a printing press having a printing cylinder; conveyor means having courses receiving printed sheets from the cylinder; a mechanism for feeding sheets to the cylinder, including a rock shaft, and means for stopping the mechanism when the rock shaft is stopped; said attachment comprising in combination a magnet support; an electro-magnet on said support; a plunger bolt slidably guided in said magnet and adapted when the magnet is energized to be withdrawn toward the magnet; a plunger rod slidably reciprocatorily guided transverse to said bolt when retracted and connected to the rock shaft and adapted to be stopped by the bolt when not retracted; a switch box

mounted under the path of the printed sheets; a switch in said box comprising a lower contact and a leaf spring biased from the lower contact; a source of current; conductors connecting said solenoid and switch in series between the terminals of said source; an upright rod resting on said leaf spring; and a feeler finger pivoted in the upper part of the switch box at the end nearest the cylinders and adapted to be pressed upwardly by said rod and leaf spring beyond the plane of the sheets when no sheet is present, thereby to open the switch and deenergize the magnet, whereby if a sheet should fail to be present over the switch when the plunger rod is about to be projected, the finger will be raised, the switch opened, and the rock shaft stopped.

8. An attachment for use on a printing press having conveyor means having courses receiving printed sheets from the press and a feed mechanism for feeding sheets to the press including an oscillatory part and means for stopping the feeding mechanism when the oscillatory part is stopped; said attachment comprising, in combination, a magnet support; an electro-magnet on said support; a guided plunger of magnetic material yieldably disposed in one position adjacent to the magnet and having a bolt part and adapted when the magnet is energized to be attracted and drawn toward the magnet to another position; a plunger rod slidably reciprocatorily longitudinally guided in a path transverse to the path of said bolt part and adapted to be connected to

the oscillatory part to be reciprocated thereby; said bolt part being constructed and positioned to allow the rod to move across its path when the plunger is in one of said positions of its movement, and when the plunger is in the other position to stop said rod thereby to stop said feed mechanism; a switch mounted adjacent to the path of the printed sheets and connected in series circuit with the coil of the electro-magnet; and a yieldable feeler connected to the switch and adapted to be pressed beyond the plane of the printed sheets when no sheet is present, thereby to operate the switch; said circuit, switch, feeler and electro-magnet being so arranged that when no sheet is present said switch is operated and electro-magnet and plunger are operated to cause said bolt part to move to position to stop said plunger rod.
